UNITED STATES PATENT OFFICE.

CHARLES R. DOWNS, OF CLIFFSIDE, NEW JERSEY, ASSIGNOR TO THE BARRETT COMPANY, A CORPORATION OF NEW JERSEY.

SULFONATION OF HYDROCARBONS WITH SO₃.

1,321,994.

Specification of Letters Patent. Patented Nov. 18, 1919.

No Drawing.

Application filed June 11, 1919. Serial No. 303,338.

To all whom it may concern:

Be it known that I, CHARLES R. DOWNS, a citizen of the United States, residing at Cliffside, in the county of Bergen and State 5 of New Jersey, have invented certain new and useful Improvements in Sulfonation of Hydrocarbons with SO₃, of which the following is a specification.

This invention relates to a method of sulfonating hydrocarbons by means of sulfur trioxid. It relates more particularly to the sulfonation of aromatic hydrocarbons by the use of gaseous SO₃. The invention has particular application in the sulfonation of 10 benzene and naphthalene in the vapor phase to produce the mono- or higher sulfonic acids by means of gaseous SO₃, such as the ordinary gas mixture obtained from the usual contact chamber for producing SO₃.

15 It is well known that when aromatic hydrocarbons are treated with sulfuric acid, water is formed as a by-product. Due to the formation of water during the sulfonation it is necessary either to use more sulfuric acid than would otherwise be required, because of the consequent dilution of the 20 sulfuric acid, or the water must be removed during the sulfonation process in order for the sulfonation to be completed.

25 When aromatic hydrocarbons are treated in the liquid phase with SO₃ to sulfonate the same, it is desirable to use pure SO₃ in order to avoid contamination of the products with objectionable matter which is not 30 easily removed. Since the ordinary SO₃ from the contact chambers is usually mixed with some SO₂, and nitrogen and other impurities, the sulfonation products will be contaminated when such impure SO₃ is 35 used.

40 By my invention it is possible to use SO₃ from the contact chambers for the sulfonation of aromatic hydrocarbons, thereby obviating the formation of water as a by-product, and also preventing the mixture of other impurities with the sulfonic acids to any appreciable extent. In carrying out this invention the aromatic hydrocarbon in the vapor phase, admixed with SO₃ from 45 the contact chambers, is passed through vessels or tubes heated to the proper temperature for the sulfonation to take place. The rapidity and degree of sulfonation and the formation of the mono-sulfonic acid or 50 higher sulfonic acids and the position that

the sulfonic acid group will take will depend upon many factors such as the temperature at which the reaction is caused to take place, the length of time the SO₃ is kept in contact with the hydrocarbon, the dilution of the SO₃ with blanketing gases, such as nitrogen, the particular hydrocarbon used, and the pressure that is maintained in the system. These factors can be easily ascertained by trial so as to produce the desired results. When the proper proportion of hydrocarbon and SO₃ is passed through the hot space substantially all of the SO₃ will react without the formation of any water, or the waste of a substantial amount 60 of SO₃. For example, if the theoretically correct amount of SO₃ is passed with naphthalene in the vapor phase through a tube heated between about 90° C. and 180° C., the mono-sulfonic acids of naphthalene 65 will be mainly formed.

70 Upon exit of the reaction products from the hot reaction chamber, the sulfonic acid will be easily condensed due to the fact that sulfonic acids have low vapor pressures, 75 while the other gases, if present, will pass off. In this way a substantially pure sulfonic acid will be condensed which is free from the presence of sulfuric acid or other products.

80 This freedom from sulfuric acid, and other products, is a decided advantage. Due to the mixture of sulfuric acid with sulfonic acid produced by the sulfonation of hydrocarbons in the usual way it is necessary to remove the sulfuric acid as by precipitation with calcium hydroxid, then filter the mixture, after which the sodium salt of the sulfonic acid is usually formed by treatment with a sodium compound and then the salt 85 is concentrated for the subsequent treatment with sodium hydroxid for the purpose of substituting a hydroxyl for the sulfo radical of the sulfonic acid. This present invention 90 avoids this difficulty since the substantially pure sulfonic acid resulting from the condensation of sulfonic acid vapor can be neutralized directly by caustic or weak acid salts of the alkaline metals without the necessity of precipitating CaSO₄. For this neutralization it is possible to use a caustic soda solution of such strength that the sodium salt 95 of the sulfonic acid is obtained as a water solution of proper concentration to be used for the purpose above mentioned.

While this process has been particularly described in connection with the sulfonation of naphthalene, it is applicable to other hydrocarbons, particularly benzene and its 5 homologues.

I claim:

1. The herein described process which comprises treating an aromatic hydrocarbon in the vapor phase with a gas containing 10 SO_3 under such conditions as to effect sulfonation of the aromatic hydrocarbon.
2. The herein described process which comprises treating an aromatic hydrocarbon in the vapor phase with a gas containing 15 SO_3 under such conditions as to effect sulfonation of the aromatic hydrocarbon, and condensing the sulfonic acids thereby formed.
3. The herein described process which 20 comprises treating an aromatic hydrocarbon in the vapor phase with a gas containing SO_3 under such conditions as to effect sulfonation of the aromatic hydrocarbon, condensing the sulfonic acids thereby formed, 25 and permitting the uncondensed gas to escape.
4. The herein described process which comprises treating an aromatic hydrocarbon in the vapor phase with gaseous SO_3 under 30 such conditions as to effect sulfonation of the aromatic hydrocarbon.
5. The herein described process which comprises treating an aromatic hydrocarbon in the vapor phase with gaseous SO_3 under 35 such conditions as to effect sulfonation of the aromatic hydrocarbon, and condensing the sulfonic acids thereby formed.
6. The herein described process which comprises treating an aromatic hydrocarbon 40 in the vapor phase with a gas containing SO_3 under such conditions as to effect sulfonation of the aromatic hydrocarbon, condensing the sulfonic acids thereby formed, and directly neutralizing said acids.

7. The herein described process which 45 comprises treating an aromatic hydrocarbon in the vapor phase with a gas containing SO_3 under such conditions as to effect sulfonation of the aromatic hydrocarbon, condensing the sulfonic acids thereby formed, 50 and directly neutralizing said acids with a compound containing an alkali.

8. The herein described process which comprises treating an aromatic hydrocarbon in the vapor phase with a gas containing 55 SO_3 under such conditions as to effect sulfonation of the aromatic hydrocarbon, condensing the sulfonic acids thereby formed, and directly neutralizing said acids with caustic soda solution of such concentration 60 that a water solution of sodium sulfonate will be formed.

9. The herein described process which comprises treating naphthalene in the vapor phase with a gas containing SO_3 under such 65 conditions as to effect sulfonation of the naphthalene.

10. The herein described process which comprises treating naphthalene in the vapor phase with a gas containing SO_3 under such 70 conditions as to effect sulfonation of the naphthalene, condensing and neutralizing the sulfonic acid thereby formed.

11. The herein described process which comprises passing naphthalene and SO_3 75 through a confined space at a temperature between 90° C. and 180° C.

12. The herein described process which comprises treating naphthalene in the vapor phase with a gas containing SO_3 under such 80 conditions as to effect sulfonation of the naphthalene, and condensing the sulfonic acid thereby formed at a temperature below that at which the major portion of the other gases will be condensed.

In testimony whereof I affix my signature.

CHARLES R. DOWNS.
